UNITED STATES PATENT OFFICE.

JOHN E. BELL, OF BROOKLYN, NEW YORK, ASSIGNOR TO SINCLAIR REFINING COMPANY, OF CHICAGO, ILLINOIS, A CORPORATION OF MAINE.

PROCESS AND APPARATUS FOR FRACTIONAL CONDENSATION.

Application filed March 23, 1922. Serial No. 545,951.

To all whom it may concern:

Be it known that I, JOHN E. BELL, a citizen of the United States, residing at Brooklyn, county of Kings, State of New York, 5 have invented certain new and useful Improvements in Processes and Apparatus for Fractional Condensation, of which the following is a specification.

Crude petroleum has heretofore been separated into the various fractions thereof corresponding to the desired commercial product and residues by fractional distillation. In this process the oil is slowly heated through the range of temperatures in which 10 the desired distillates are given off, the vapors being condensed as they issue from the still. Cuts or divisions are made at successively higher temperatures, the points at which the cuts are made being determined 15 by the gravities of the components which are to be embraced in the respective fractions or cuts, as they are commonly called, which after refinement constitute the commercial products. In practice, however, it 20 has been found possible only to approximately separate the compounds into fractions according to their gravities, some of the compounds of heavier gravities being carried over with those of lighter gravities, 25 and some of the lighter oils remaining after the temperature has been raised above their boiling point and so forming a portion of the cut or fraction intended to contain only heavier oils. It has therefore been necessary 30 in order to secure a sufficiently sharp division between the cuts and to prevent the respective commercial products from containing oils of lighter or heavier gravities than they are designed or intended to contain to re-run or re-distill the product of 35 the first distillation. Such re-distillation, however, is expensive, requiring costly additional apparatus, consuming large quantities of fuel, and requiring the attention 40 of additional operatives.

It is the purpose of the present invention to avoid this additional expense by effecting the separation of the components of the oil into their respective groups or cuts with sufficient thoroughness in a single operation 45 for commercial purposes. It is known that

the sharpness of cut in a condenser depends upon the temperature difference between the vapors condensed and the condensing surface or medium, the nearer the latter 50 approaches in temperature the vapors to be condensed the sharper being the cut. On the other hand, the less the temperature difference the less effective the condenser, or otherwise put, the larger must be the contact surface to secure the same amount of 55 condensation. In practice, therefore, compromise must be made between efficiency of operation and sharpness of cut and it becomes important to so control the temperature of the condenser that the essential degree of sharpness of cut is attained without 60 too much sacrifice of efficiency. One of the objects of the present invention is to provide a process and apparatus by which it is possible 65 to secure the desired number of cuts while causing each cut to be condensed at a temperature slightly below, but sufficiently near that of the vapors being condensed to 70 secure the required degree of sharpness. For 75 this purpose I carry on the condensation process by means of a cooling medium which is continuously circulated, and I control the temperature of the medium by replacing a portion of it with fresh cooling medium 80 from time to time during such circulation. The cooling medium I prefer to use is air and in the condensing apparatus this air is circulated through pipes which constitute 85 the condensing surfaces. During such circulation more or less of the air in the condenser is replaced by cooler air from the atmosphere so that the desired temperature gradient may be secured throughout the condenser. The vapors coming from the 90 still are brought into contact with hot but successively cooler surfaces, so that the components thereof are condensed in the order of their gravities, or substantially so, the condensates as formed being either drawn off 95 in separate cuts or first submitted to more or less re-distillation in the condenser by contact with the vapors of higher temperature, before leaving the apparatus. For 100 this latter purpose the apparatus is arranged in the form of a series of chambers through which the vapors to be condensed

are successively introduced. Condensation occurs in each of these chambers and the condensate so formed is introduced into the chamber prior in series and mingled with 5 the condensate formed from the vapors in that chamber. In such mingling, however, the condensate first mentioned is brought into direct contact with the vapors flowing through that chamber, and these vapors 10 bring about the redistillation referred to.

In the accompanying drawing and following specification I have disclosed two embodiments of apparatus embodying the invention and in which the new process may 15 be carried on; it is to be understood, however, that the specific disclosures are for the purpose of exemplification only and that the scope of the invention is defined in the following claims in which I have endeavored 20 to distinguish it from the prior art so far as known to me without, however, relinquishing or abandoning any portion or feature thereof.

The simpler embodiment of the apparatus is shown in Figs. 1 to 3 of the drawing and the preferred form in Figs. 4 to 6 thereof. Fig. 1 is a plan of the simpler embodiment; Fig. 2 a vertical section on line 2—2 of Fig. 1 on an enlarged scale; Fig. 3 a 25 vertical section on a similar scale on line 3—3 of Fig. 1 looking in the direction of the arrows, parts being shown in elevation; Fig. 4 a plan of the preferred form of the apparatus; Fig. 5 a vertical longitudinal 30 section thereof, and Fig. 6 a vertical section on line 6—6 of Fig. 5. Each part is identified by the same reference character wherever it occurs in the several views.

Referring first to the simpler form of the 35 apparatus shown in Figs. 1, 2 and 3, the condenser will be seen to comprise a number of condensing elements a' , a^2 , etc., which are identical in construction and operation except in respects hereinafter pointed out, 40 and therefore a description of one will serve for all. A cylinder 7 is fitted with heads 8, 9 which may be held in place by bolts 10. The heads 8, 9 throughout corresponding 45 rectangular areas are bored and connected by tubes 11 for the passage of air. Air ducts 11^a cover the perforated areas of the respective heads and communicate with said tubes to provide for the circulation of air through 50 the tubes of all the elements in series. These 55 elements a' and a^2 , a^3 and a^4 , a^5 and a^6 are connected on one side of the series by the U-shaped air conduits 12, 13 and 14, and elements a^2 and a^3 , a^4 and a^5 , are connected on 60 the other side of the series by similar air 65 conduits 15 and 16. An air pump 17 driven by motor 18, circulates air through the series of condenser elements, the intake side of the pump being connected by conduits 19, 20 to the element a and the exhaust pipe 70 to element a^6 by conduit 21.

In order to regulate the temperature of the air and reduce it to that necessary to maintain the desired temperatures of the condensing surfaces I may provide for the replacement of a portion of the air by fresh 70 or cooler air. For this purpose an air outlet 22 and an air inlet 23 are provided, controlled respectively by dampers 24, 25. The circulation may be regulated by damper 26, 75 all of said dampers being provided as usual with means for holding them in adjusted position.

The vapors as they come from the still or from another condenser by which their heavier components have been removed, are 80 circulated through the series of condenser elements preferably in a direction the reverse of that in which the air is circulated, so that the air in its cooler state acts upon the vapors after their temperature has been 85 lowered. For this purpose elements a' and a^2 , a^3 and a^4 , a^5 and a^6 are connected near their ends on one side of the series by U-tubes 27, 28, 29, respectively, and elements 90 a^2 and a^3 , and a^4 and a^5 , near their opposite ends have similar U-tubes 30, 31. Element a' is provided with an inlet 32 which may be connected to a still or another condenser, as previously explained, and element a^6 has an outlet 33 which may lead to a further 95 condenser or storage receptacle for vapors or gases or both. Thus the vapors pass through the condenser elements in succession and in contact with the air-conveying tubes 100 therein.

Preferably in order to secure more thorough circulation of the vapors about the tubes the group of tubes in each cylinder is boxed in on opposite sides by plates 34, 35, and each element is provided with a baffle 105 36 to compel the gases to traverse the group of air pipes twice, and baffles 37, 38 to spread the vapors in the chamber.

Each condenser element has a draw-off 110 39 for condensates, so that a separate cut can be taken off from each element.

Thermometer wells or mountings are provided in each air conduit as at 40 and in each vapor conduit as at 41, whereby temperature conditions may be observed. The 115 condenser elements are shown as mounted in a bed of fire-brick 42, the condenser as a whole being partially enclosed in a boxing 43 supported on beams 44.

In carrying out the process by means of 120 the apparatus described the heat of the vapors is absorbed continuously as they circulate through the condensing elements of the series, consequently there is condensate formed in each element, the heaviest vapors 125 condensing and forming a cut in the first element, the next heaviest in the second element, and so on, and each cut may be drawn off from the element in which it is formed and either used unmixed, or combined with 130

suitable proportions of other cuts to form a commercial product. The air may be circulated through the apparatus without admixture of cooler air and so heated to a temperature very little below that of the vapors, in which case the temperatures of the condensing surfaces will be correspondingly high and the cuts sharply defined. In order to secure greater condensation, however, I ordinarily prefer to mix more or less cooler air continuously with that circulated through the condenser, this being accomplished by so regulating the valves 23, 24 that there is continuous exhaust of heated air and influx of cooler air, the amount of replacement being determined by observing the readings of the thermometers in the various wells and adjusting the valves accordingly.

The process as carried out by the apparatus shown in Figs. 4, 5 and 6 is in the main similar to that carried on by the apparatus already described, involving the circulation of vapors in contact with air cooled surfaces maintained at successively diminishing temperatures by circulation of air, the temperature of which is controlled by admixture of cooler air therewith. In the apparatus to be now described a single continuous body 45 replaces the condenser elements of the previously described form and is so partitioned by baffle plates as to provide for a series of chambers or compartments through which the vapors pass successively and from which the desired cuts may be separately removed.

As best seen in Fig. 5 the condenser body 45 is provided at its ends with end walls 45^a, 45^b, in which are inserted headers 46, 47 connected by tubes 48 extending longitudinally of the body and through which air is circulated, as will presently appear.

A vapor inlet 49 in the top of the condenser body near one end thereof is connected to the vapor line of the still or to a higher temperature condenser and a vapor outlet 50 near the other end to a cooler condenser in which the uncondensed vapors may be further treated. The vapor space of the condenser is divided by vertical baffles 51, 52, baffles 51 extending from the top of the condenser nearly to the bottom thereof and baffles 52 from the bottom nearly to the top, so that the vapors entering by the inlet are forced to a circuitous or zigzag course, traversing the battery of air cooled pipes back and forth many times before reaching the outlet. It will be observed that the passages for the vapors between the baffles are much larger near the vapor inlet, diminishing toward the outlet as the volume of vapors is decreased by condensation.

The bottom sections 53, 54, 55, 56 form pockets with baffles 52 for the reception of separate bodies or cuts of condensate formed

in the respective vapor spaces between said walls and baffles immediately above. Preferably the bottom is stepped, the bottom sections being at successively higher levels from the inlet to the outlet end of the condenser for a purpose which will appear. Each division or compartment of the condenser is provided a short distance above its bottom, with a header 57 constituting a false bottom in which are secured numerous upwardly extending short lengths of tube 58. A drain pipe 59 is also secured in an opening in each header or false bottom except that at the inlet end of the condenser, and communicates with the space between the bottom and header of the compartment to the right. As the vapors are cooled in their passage through the condenser the heaviest group or cut is condensed in the first or extreme right hand compartment (as seen in Fig. 5), the next heaviest in the second compartment, and so on, and the condensates collect in the respective lower ends of said compartments, above the false bottoms between and around the tube sections mounted therein. The condensate collecting on any false bottom (except the first) passes from the overflow pipes 59 to the space below the false bottom in the preceding compartment whence the condensate passes upwardly through the tubes 58 and overflows or cascades from the upper ends of these tubes into the space above the false bottom where it mixes with the condensate surrounding these tubes. In thus overflowing the mixed condensate is subjected in a series of thin films to the hotter vapors circulating about the tube sections and over the ends thereof and the more volatile components, particularly those which have refluxed from the adjacent somewhat cooler compartments are revaporized and intermingled with the passing vapors. At the same time the exposure of the passing vapors to the films of condensate above and about the tubes 58 condenses more or less of the heavier components thereof. It will be noted that the baffle 51 extends down closely to the top of the tubes 58, forcing the vapors to pursue a path about such tubes, thus assuring intimate contact between the condensate films and the vapors, and furthermore, that the descent of the vapors in a vertical path on the one side of each baffle 51 followed by the sharp reversal of flow on the other side thereof tends to deposit any drops or particles of liquid condensed in the lower end of the compartment.

Referring more particularly to Figs. 4 and 5, the headers 46, 47 are seen to be surrounded or covered by hoods 71, 72 respectively. Hood 72 is connected by a reduced neck 73 with a fan chamber 74 containing a fan 75, and the latter is driven by a motor 76 of any suitable or approved type. Hood 71 and fan chamber 74 are

connected by an air conduit 77 (see Figs. 4 and 6) so that air may be continuously circulated by fan 75 through a closed circuit through conduit 77, hood 71, condenser tubes 48, hood 72, neck 73 and fan chamber 74.

In order to properly control the temperature of the condensing surfaces formed by said tubes I provide for the replacement 10 of any desired portion of the hot air in the circuit by cooler air. For this purpose hood 72 is formed with an escape flue 79 having a butterfly valve or damper 80 therein, and neck 73 is open to a collar 81 slotted at suitable intervals as at 82 and surrounded by a rotary slotted sleeve 83, the slots of which may be caused to completely or partially register with the slots in the collar so as to provide inlets for cooler 20 air. Obviously, by adjusting the sleeve 83 and valve 80 the amount of air replaced per unit of time may be closely regulated and thus the temperature of the entire body of air in the apparatus and of the condensing 25 tubes accurately controlled. If very little temperature differential between the condensing surfaces and the vapors is desired it has been found that sleeve 83 may be so positioned as to close the apertures 82 and butterfly valve 80 closed, when the temperature of the air will be reduced only by such fresh air as enters crevices in the construction, and by such cooling as is effected in the conduit 77 because of the 30 exposure of the latter to the atmosphere.

In order to closely observe the temperature thermometer wells 88 are provided at suitable points in the condenser. Instead of introducing the vapors at inlet 49 all 40 or a portion thereof may be introduced at the inlet 89 arranged, as shown in Fig. 5, midway of the condenser. In some instances it may be desirable to introduce at the inlet 49, certain vapors and at inlet 89 other vapors which lack some of the heavier constituents of the vapors introduced at inlet 49.

It will be seen that in the process as carried on by the apparatus just described, the vapors to be condensed flow successively 50 through a series of chambers the temperatures of which gradually diminish. The cooling medium, air, flows through the condensing apparatus in a direction opposite to the direction of flow of the vapors to be 55 treated and the temperature of this cooling medium is continuously regulated by replacing a portion of it with fresh air during its circulation. Cuts may be separately collected from each of the chambers or the 60 condenser may be used for producing a single cut, in which event the condensate may be withdrawn from the bottom of the first condensing chamber which has received the condensates from the chambers later in 65 series. Where a single cut is so produced,

the condensates formed in each chamber (except the first) are then exposed to successive redistillation by direct contact with the vapors flowing in the chambers prior in series, and this permits of a much greater 70 sharpness of cut by reason of the redistillation and condensation of the cuts. The temperature of the cooling medium in any chamber is only slightly below that of the vapors passing through that chamber and 75 this permits the condensation to occur under those conditions which are most conducive to sharpness of cut.

I claim:

1. A process of the class described which 80 comprises passing the vapors to be condensed into heat exchange relationship with a cooling medium moving through a closed circuit, and regulating the temperature of the medium by replacing a portion thereof with 85 fresh cooling medium.

2. A process of the class described which 90 comprises passing the vapors to be condensed into heat exchange relationship with a cooling medium, moving through a closed 95 circuit, removing heat from said medium during such movement and while it is out of such relationship, and regulating the temperature of the medium by replacing a portion thereof with fresh cooling medium.

3. A process of the class described which 100 comprises passing the vapors to be condensed through a series of compartments in heat exchange relationship with a cooling medium moving through a closed circuit, collecting the condensate formed in each compartment and exposing the condensate formed in each compartment (except the first) to the vapors flowing through a compartment prior in the series.

4. A process of the class described which 110 comprises passing the vapors to be condensed through a series of compartments in heat exchange relationship with a cooling medium flowing through a closed circuit, collecting the condensate formed in each compartment and successively exposing the condensate formed in each compartment (except the first) to the vapors flowing through the compartments prior in the 115 series.

5. A process of the class described which 120 comprises passing the vapors to be condensed through a series of compartments of diminishing size in heat exchange relationship with a cooling medium moving through a closed circuit, and regulating the temperature of the medium by replacing a portion thereof with fresh cooling medium.

6. A process of the class described which 125 comprises passing the vapors to be condensed through a series of compartments in heat exchange relationship with a cooling medium moving through a closed circuit, withdrawing the condensate formed from 130

the bottom of each compartment and introducing the condensate formed in each compartment (except the first) into the bottom of a compartment prior in the series in direct contact with the vapors flowing therethrough.

7. A process of the class described which comprises passing the vapors to be condensed through a series of compartments in heat exchange relationship with a cooling medium moving through a closed circuit through all the compartments, collecting the condensate formed in each compartment, exposing the condensate formed in each compartment (except the first) to the vapors flowing through a compartment prior in the series, and mingling this condensate with the condensate formed in that prior compartment.

8. A process of the class described which comprises passing the vapors to be condensed through a series of compartments in heat exchange relationship with a cooling medium moving in a closed circuit through all the compartments, collecting the condensate formed in each compartment and introducing it into a compartment prior in the series, while exposing it to the vapors flowing through that compartment, mingling the condensate with the condensate formed in the prior compartment and mingling the vapors given off by the condensate first mentioned during such exposure with the vapors flowing through the compartment.

9. A process of the class described which comprises passing the vapors to be condensed through a series of compartments of diminishing size in heat exchange relationship with a cooling medium flowing in a closed circuit through all the compartments, causing the condensate formed in each compartment (except the first) to overflow into a compartment prior in series in direct contact with the vapors passing therethrough, and regulating the temperature of the medium during its movement by replacing a portion thereof with fresh cooling medium.

10. In an apparatus of the class described, a condensing chamber having a vapor inlet, cooling tubes extending through said chamber and constituting condensing surfaces, a closed circuit including said tubes, means for circulating the cooling fluid through said circuit, and means regulating the temperature of the medium in said circuit by replacing a portion thereof with fresh cooling medium.

11. In an apparatus of the class described, a condensing chamber having a vapor inlet, tubes extending therethrough, the surfaces of which constitute condensing surfaces, a conduit connected at its respective ends to the opposite ends of the tubes, air forcing means in the conduit, means for admitting

fresh air to the conduit, and means for permitting the escape of air therefrom.

12. In an apparatus of the class described, a condensing chamber, a vapor inlet at one end thereof and a vapor outlet at the other end thereof, the bottom of the chamber comprising a series of sections each successively raised with respect to the adjacent section nearer the vapor inlet, baffle extending upward from said bottom intermediate said sections and forming pockets therewith, and means for conducting condensate from each bottom section except the lowest one to the next lower section.

13. In an apparatus of the class described, a condensing chamber, a vapor inlet at one end thereof and a vapor outlet at the other end thereof, the bottom of the chamber comprising a series of sections each successively raised with respect to the adjacent section nearer the vapor inlet, baffles extending upward from said bottom intermediate said sections and forming pockets therewith, horizontal headers in each of said pockets above and spaced from the bottom section thereof, tube sections extending through said headers and above the same, and pipes connecting the space above said header of each section except the lowest one with the space below the header of the adjacent section toward the vapor inlet.

14. In an apparatus of the class described, a condensing chamber, a vapor inlet at one end thereof and a vapor outlet at the other end thereof, the bottom of the chamber comprising a series of sections each successively raised with respect to the adjacent section nearer the vapor inlet, baffles extending upward from said bottom intermediate said sections and forming pockets therewith, baffles intermediate the first-mentioned baffles and extending from the top of the chamber nearly to the bottom thereof, headers arranged in each pocket above and spaced from the bottom of the pockets, overflow tubes in each header extending above the same, and a connection from the space above each header except the lowermost to the space beneath the header in the adjacent pocket toward the vapor inlet.

15. In an apparatus of the class described, a condensing chamber, a vapor inlet at one end thereof and a vapor outlet at the other end thereof, a series of transverse baffles extending upward from the bottom of said chamber and forming pockets therein for the reception of condensate, cooling means extending through said chamber, an offtake from each pocket and means for conducting the condensate from each pocket except that nearest the vapor intake and injecting it into the adjacent vapor pocket nearer the vapor intake.

16. In an apparatus of the class described, a condensing chamber having a vapor inlet

at one end thereof and a vapor outlet at the other end thereof, cooling means extending through said chamber, partitions dividing the lower portion of the chamber into a longitudinal series of pockets, a false bottom in each of said pockets forming a chamber beneath the same, a pipe section extending above said false bottom and communicating with the space below the same and a pipe opening above each false bottom, except that nearest the vapor inlet and communicating with the space beneath the adjacent false bottom nearer the vapor inlet.

JOHN E. BELL.
